JAMES HOLLAND, OF CONSHOHOCKEN, PENNSYLVANIA.

Letters Patent No. 73,010, dated January 7, 1868.

IMPROVEMENT IN BOOTS.

The Schedule referred to in these Letters Patent and making part of the same.

TO ALL WHOM IT MAY CONCERN:

Be it known that I, JAMES HOLLAND, of Conshohocken, county of Montgomery, State of Pennsylvania, have invented an Improvement in Boots; and I do hereby declare the following to be a full, clear, and exact description of the same.

My invention relates to that class of boots having pockets in the legs, formed by stitching to the leg a strip or strips of leather or suitable fabric, each strip being folded over the upper edge of the boot, and secured to the outside of the same by buttons or other suitable fastenings, the pockets thus formed affording, for travellers and others, convenient and secure receptacles for bank-notes and other valuables of small bulk; and my invention consists in applying a wire to the upper edge of the boot, so that attempts of pickpockets to cut through the latter may be frustrated.

In order to enable others to make and apply my invention, I will now proceed to describe the mode of carrying the same into effect, reference being had to the accompanying drawing, which forms a part of this specification, and in which—

Figure 1 represents a side view of a boot partly in section, to illustrate my improvement,

Figure 2 an exterior view of the boot, and

Figure 3 a sectional plan on the line 1-2, fig. 1.

Similar letters refer to similar parts throughout the several views.

I form two pockets in the inside of the leg of a boot, by stitching to the same two strips, A and A', of leather, or substantial fabric. Both strips are stitched to the leg near the usual vertical seams *a*, the strip A being adapted to the front, *b*, and the strip A' to the rear, *b'*, of the leg, so that they present no obstruction to the pulling of the boot on to the foot in the usual manner. The lower edges of the strips are securely stitched to the leg of the boot, over the upper edge of which the strips are folded, as seen in fig. 2, and secured by buttons or other suitable fastenings.

The pockets thus formed between the inside of the leg and the strips stitched to the same, afford for travellers and others convenient receptacles for bank-notes and other valuables of small bulk, and to which pickpockets cannot gain access without disturbing the wearer of the boot.

As a preventive against any attempt of thieves to cut downwards into the pockets, I secure to the upper edge of the boot, within the fold of the strip which forms the pocket, a ring, *d*, of steel or other hard metal, or a bent wire, which cannot be readily severed.

I claim as my invention, and desire to secure by Letters Patent—

A metal ring or bent wire, *d*, applied to the upper edge of the boot-leg, within the folds of the strips A and A', as set forth, for the purpose specified.

In testimony whereof, I have signed my name to this specification in the presence of two subscribing witnesses.

JAMES HOLLAND.
